UNITED STATES PATENT OFFICE.

ALBERT S. REEVES, OF MILLVILLE, NEW JERSEY, ASSIGNOR OF ONE-HALF
TO DANIEL SILVERS AND WILLIAM T. CORSON, OF SAME PLACE.

CAR-COUPING.

SPECIFICATION forming part of Letters Patent No. 326,590, dated September 22, 1885.

Application filed May 13, 1885. (No model.)

To all whom it may concern:

Be it known that I, ALBERT S. REEVES, of Millville, in the county of Cumberland and State of New Jersey, have invented certain new and useful Improvements in Car-Couplings; and I do hereby declare the following to be a full, clear, and exact description of the invention, such as will enable others skilled in the art to which it appertains to make and use the same.

My invention relates to an improvement in car-couplers, the object of the same being to provide a coupling by means of which cars of different heights may be automatically coupled, and whereby the same may be uncoupled without necessitating the entrance of a brakeman or other operator between the cars. A further object is to provide a coupling of this character which shall be simple and economical in construction and durable and efficient in use; and with these ends in view my invention consists in the certain features of construction and combinations of parts, as will be hereinafter fully described, and pointed out in the claims.

In the accompanying drawings, Figure 1 is a view in plan and side elevation of my improvement, showing the link in position for coupling, and Fig. 2 is a view showing the link secured out of possible contact with the adjacent link.

B represents one of the beams of the car, to which is centrally secured the bracket D, and a forward beam, C, is likewise provided with a yoke, E, the ends being secured to the beam, thus forming a closed guide.

To the bracket D is pivotally secured the rear end of the draw-head F, the forward end of the same passing through the yoke E, whereby it is confined relative to its vertical and lateral play. The forward end of the draw-head is bifurcated, thus adapting it to receive the rear end of the link G, which is pivoted between the arms of the draw-head, as shown at H.

The forward end of the link G is provided with the arrow-shaped head H, with the beveled faces thereof on a horizontal plane with the body of the car, whereby the link is adapted to engage an approaching link of similar

construction, whether the links should be secured to cars at different heights or not.

To the rear portion of the link G is rigidly secured one end of the yoke H, the opposite end of said yoke being provided with the perforation I, which is adapted to engage the free end of the rod or pin J, which is rigidly secured at one end to the draw-head F. The pin J is provided with a spiral spring, K, which encircles the same, the ends thereof impinging against the draw-head F and the yoke H, respectively, whereby the end of the yoke which is secured to the link is caused to bear against one side of the draw-head, and consequently hold the link in direct adjustment 65 therein. The bar H³ is pivoted on the end of the yoke, thus permitting it to be in direct adjustment on the pin J when the yoke proper is in oblique adjustment.

To the free end of the link G is secured the chain L in any preferred manner, the opposite end of the said chain being secured to the lower end of the lever M, the said lever being pivotally secured to one end of the car. Thus it will be seen that when it is desired to uncouple the cars, by canting the lever to one side it will cause the link to become disengaged.

The upper portion of the draw-head F is provided with the recess N, in which is pivotally secured the link O, the said link being adapted to receive a pin, and when it is necessary to use a link of this character the link G is locked out of possible engagement by means of the lever M, which is canted to one side and secured in such position on the rock-bar P, which is secured to the top of the car, as shown; or, if the coupling should be attached to a box-car, the lever may be arranged differently, as, for instance, it may be secured to the side of the car in any suitable manner.

It will be seen that by employing the spring K, when the link is drawn to one side and uncoupled, the spring will immediately cause the link to return to its original position in the draw-head, and so be in readiness for coupling.

I would have it understood that I do not limit myself to the exact construction shown and described, but consider myself at liberty 100

to make such changes and alterations as properly fall within the spirit and scope of my invention.

Having fully described my invention, what I claim as new, and desire to secure by Letters Patent, is—

1. The combination, with a draw-head and a link pivoted at a point between its ends to said draw-head, of the yoke secured to the rear end of the link and a spring located between the yoke and the draw-head, substantially as set forth.

2. In a car-coupling, the combination, with a draw-head pivoted to the car-frame, of a link pivoted to the draw-head, a yoke secured to the rear end of the link, a spring adapted to impinge against the draw-head and the yoke, and a lever and connecting devices

whereby the link is locked out of coupling adjustment, substantially as set forth.

3. As a new article of manufacture, a car-coupler consisting, essentially, of the draw-head having two recesses therein, a laterally-movable link or hook-coupler, and the link *o*, the said hook-coupler and link being secured at one end within their respective recesses, and a spring for holding the hook-coupler in position to engage a similar hook on the next car, substantially as set forth.

In testimony whereof I have signed this specification in the presence of two subscribing witnesses.

ALBERT S. REEVES.
